UNITED STATES PATENT OFFICE

HARRY S. HUMPHREYS, OF LANCASTER, PENNSYLVANIA, ASSIGNOR TO ARMSTRONG CORK COMPANY, OF LANCASTER, PENNSYLVANIA, A CORPORATION OF PENNSYLVANIA

SURFACE ORNAMENTATION AND METHOD OF EXECUTING THE SAME

Application filed April 11, 1927. Serial No. 182,575.

This invention relates to a surface ornamentation, and more particularly to a design for a rug. The design is formed with a border and a field portion, or with a border, a field and a medallion. Certain portions of the border design are repeated throughout the field. In other cases certain of the decorative figures in the border are repeated throughout the field and are present in the medallion. Decorative figures appearing in the field may also appear in the medallion. A design of the nature described is executed by utilizing a plurality of figure-forming devices adapted to transfer a design to the ornamented surface, such as printing blocks or stencils. A number of the figure transferring devices are employed to form a border and at least one of the border forming devices is repeatedly used in laying decorative figures in the field of the rug. Where a medallion appears, one of the figure-forming devices may be used at regular intervals throughout the rug from one border through the field and medallion to the opposite border. The invention is particularly adapted for use in effecting designs on rugs of linoleum of either the printed or molded inlaid types or similar hard surfaced floor coverings such as printed felt base goods, and the figure-forming devices employed may comprise printing blocks or stencils, according to the nature of the finished article and the design to be executed.

In printing rugs, it has been necessary heretofore to employ a printing machine having a large number of printing blocks if it is desired to execute a rug design having a border, a medallion, and a field design, or to greatly restrict the number of colors employed. I provide a method of printing and a design wherein certain of the printing blocks are used repeatedly throughout the pattern. At least one of the printing blocks may be used in the border, the field, and a medallion, while other blocks may be used in both the field and medallion, or in the border and field. By using the blocks a number of times throughout the design, I am enabled to produce a pattern of this type, (that is, a rug having border, field and medallion) executed

in a greater number of colors than has heretofore been possible on a machine employing as few blocks as I employ. I am also enabled to produce a more intricate design on a machine limited to a relatively small number of printing blocks.

In the accompanying drawings illustrating certain preferred embodiments of my invention,

Figure 1 shows a portion of a floor covering printed according to my invention;

Figures 2, 3, 4, 5, 6, 7, 8 and 9 illustrate printing blocks employed in producing the pattern shown in Figure 1;

Figure 10 shows an inlaid design applied through stencils; and

Figures 11, 12, 13, 14 and 15 illustrate stencils used in forming the design shown in Figure 10.

Referring to the illustrated embodiment, there is shown in Figure 1 a rug having a border 2, a field portion 3, and a medallion 4. In printing this design, the printing blocks shown in Figures 2 to 9, inclusive, are employed in the following manner:

The printing blocks shown in Figures 2, 4, 5 and 7 all print in positions A and E in Figure 1; the blocks illustrated in Figures 3, 5, 6 and 8, print in positions B and D; and the blocks illustrated in Figures 3, 5, 6, 8 and 9 print in position C. It will thus be seen that the block shown in Figure 5 prints in all positions; the blocks shown in Figures 6 and 8 print in the field positions B and D and in the medallion position C; the block shown in Figure 2 being a border block prints only in positions A and E. In the design shown in Figure 1, I print a double border, a field and a medallion, using but eight blocks. The number of blocks employed may, of course, vary with the design and the number of colors desired. It will be evident, however, that in my design the effectiveness of a printing machine is materially increased by reason of the great number of designs and color combinations possible with a limited number of blocks.

If desired, the position C may be extended to cover a longitudinal distance greater than the width of one block to effect an elongated

medallion, simply by repeating the design shown in position C in Figure 1.

The printing blocks are illustrated as being of the usual sawn type, effective for transferring a continuous even film of paint to the covering. It will be understood, of course, that the invention is not limited to a particular type of printing block, but that various kinds of figure laying devices may be employed.

Figure 10 illustrates a molded inlaid linoleum rug employing no center medallion but having a border and a field with portions of the border design repeated throughout the field. In making molded inlaid linoleum, the granular linoleum mix is laid in the desired configuration upon the burlap backing by means of stencils, and afterward consolidated by pressure into the finished linoleum sheet, as will be readily understood by one skilled in the linoleum making art. The stencils shown in Figures 11, 12 and 13 are used in positions A' in Figure 10, while the stencils shown in Figures 11, 14 and 15 are used in positions B' in Figure 10. It will be seen that the stencil illustrated in Figure 11 is repeated throughout the whole of the design effecting a portion of the border design and also a portion of the field design. It will be obvious that the field may be extended as desired, depending upon the size of rug it is desired to make.

By the method described, I am able to effect designs upon rugs of various sizes without changing printing blocks or stencils employed, by merely changing the number of times the blocks are effective. The design shown in Figure 10 may, of course, be extended any desired length. The design shown in Figure 1 may be made in a number of sizes by repeating position C a number of times to effect an elongated medallion or by repeating the position B and D two or more times. It will be understood, of course, that the designs shown are by way of illustration only and are diagrammatic to a certain degree.

The rug illustrated in Figure 10 has been described as being decorated by means of stencils whereby an inlaid ornamented surface is produced. It will be understood, however, that the same configuration may be effected by means of printing blocks having the desired decorative figures executed thereon. It will also be understood that the design illustrated in Figure 1, having a medallion in the field, may be effected in an inlaid rug as well as in a printed covering.

The design shown in Figure 10 has been described as an inlaid rug, requiring stencils for the transfer of decorative figures thereto. Only the stencils necessary for transferring the surface decoration have been illustrated, and it will be understood that other stencils will be employed to lay

the background on an inlaid rug of this type. If the rug shown in Figure 10 were printed, the number of printing blocks could then be limited to the stencils shown in Figures 11 to 15 inclusive, since the background of the rug could be formed of the material upon which the printed decoration is applied.

Whether the rug be printed or inlaid, however, it is desirable that the designs be executed so that a plurality of rugs are formed continuously upon a sheet of floor covering, the rugs being subsequently severed at the middle line of the double border joining the adjacent designs.

While I have illustrated and described certain preferred embodiments of my invention, it will be understood that the invention is not limited thereto, but may be otherwise practiced and embodied within the scope of the following claims:

I claim:

1. The method of forming a design for a rug of linoleum or other similar hard surfaced floor covering wherein there is a cross border at each end of the rug and a field, which comprises advancing the strip material to be decorated in uniform sections beneath decorating stations, applying a decoration common to the field in every section in the length of the rug, and applying a cross border decoration at the beginning and end of each rug at the same station, no part of the field pattern being applied at the cross border station.

2. In the method of forming a series of connected rugs having an end border design, a field design and a medallion within the field, the steps consisting in applying design elements, uniformly spaced, along the material, applying other design elements in groups therewith, applying cross border elements between said groups, certain of the first-mentioned design elements cooperating with the cross border elements and forming a part of the cross border of the rugs thus formed, and applying still further design elements in said groups, which last-mentioned design elements cooperate to form a rug medallion.

In testimony whereof I have hereunto set my hand.

HARRY S. HUMPHREYS.
